DORSEY FROST ASBURY, OF WASHINGTON, DISTRICT OF COLUMBIA.

IGNITION MEANS AND METHOD.

1,364,065.

Specification of Letters Patent.

Patented Jan. 4, 1921.

Application filed February 19, 1918. Serial No. 218,083.

To all whom it may concern:

Be it known that I, DORSEY F. ASBURY, a citizen of the United States, residing at Washington, District of Columbia, have invented certain new and useful Improvements in Ignition Means and Methods; and I do hereby declare the following to be a full, clear, and exact description of the invention, such as will enable others skilled 10 in the art to which it appertains to make and use the same.

My invention relates to means and method for igniting the charges of explosive engines and has for its objects to assure ignition of a charge regardless of an oil flooded condition of the cylinder, poor compression or poor grade of gas; to provide the cylinder with an elongation the outer end of which constitutes the gas inlet and igniting 20 the charge at the inlet end of the elongation with ignited gas of a previous explosion and at the other end of the elongation with an electric spark; and to provide the cylinder with an elongation the outer end of 25 which constitutes the gas inlet and igniting the charge at the inlet end of the elongation with ignited gas of a previous explosion and thereby raise the compression, and then igniting the charge at the other end of the 30 elongation with an electric spark; to produce the initial explosion of a plural cylinder engine electrically and then continue the explosions by transferring ignited gas from cylinder to cylinder.

My improved means and method of ignition is applicable to all kinds of explosive engines irrespective of their construction or the number of cylinders employed, but for the purpose of disclosure I will show and 40 describe my invention as applied to a four cylinder four stroke cycle type, it being understood that the invention is in no way limited to this type or number of cylinders and that it permits of wide variation without departing from its scope.

In the drawings chosen to illustrate my invention, the scope whereof is set forth in the claims.

The figure is a longitudinal section of a 50 four cylinder four stroke cycle explosive engine embodying my invention.

Referring now particularly to the drawings, A indicates the engine case casted to form cylinders B, C, D and E. The case A

includes a removable top casting F shaped 55 to form explosion chamber elongations, those associated with the explosion chambers of the cylinders B and E being indicated at 10 and 13, respectively. These elongations lead to a common valve chamber 14 included in 60 the top F and extending vertically through the latter. Mounted in the case A is a crank shaft 15 and operatively mounted in the cylinders B, C, D and E are the usual pistons 16, 17, 18 and 19 respectively which latter are connected respectively with the crank shaft 15 by connecting rods 20. Rotatably mounted in the chamber 14 is a valve G provided with an exhaust port 21 and a supply port 22 both of which open through the 70 side of the valve. This valve during its rotation controls the supply and exhaust of gases in the manner described and claimed in my co-pending application; filed Jan. 4, 1918, Serial No. 210,280. 75

The arrangement of the elongations of the explosion chambers around the valve chamber 14 is such that an explosion of a charge is always produced by ignited gas collected from the last explosion and such 80 ignited gas is moved a minimum distance in order to effect its transfer from one chamber to another. By this arrangement I secure a very quick delivery of the ignited gas after its collection and avoid any possibility of it cooling to an extent that would 85 destroy its effectiveness as an igniting medium.

The cylinders B, C, D and E have associated therewith respectively spark plugs 90 36', 37, 38 and 39 of an electrical ignition system, the use of which in conjunction with my system of gas ignition will produce certain advantageous results that will herein-after appear, but it should be understood 95 that such a combined system of ignition is not necessary to the fundamentals or my invention as complete effective ignition will be had by the use of exploded gas as an igniting medium without recourse to electrical 100 ignition other than for the purpose of producing the initial explosion. However, by placing the spark plugs at the inner ends of the elongations of the explosion chambers and delaying the operation of respective 105 plugs until after ignited gas has been introduced into the related elongation I materially reduce the time of complete combus-

tion of the charge for the reason that the charge is ignited at two points and the spark plug is operated after the compression has been raised by the ignition of the charge by 5 the gas of a previous explosion. By shortening the time of combustion of a charge in this manner I eliminate the necessity of advancing and retarding the spark. It will be noted that the ignited gas is introduced into 10 the elongations of the explosion chambers at their ends nearest the gas supply and for this reason the ignited gas will always be brought into contact with the best mixture and this condition, whether electrical ignition 15 is or is not utilized, will assure ignition of the charges irrespective of an oil flooded cylinder, poor compression or poor grade of gas.

Assuming that the operation of the engine 20 has been instituted electrically and the electric ignition then cut out, the cylinder D is firing and during high compression therein the ignited gas will collect in the cavity 36 and be transferred by the movement of 25 the valve G to the cylinder E where it will ignite the charge in the latter. From this explosion a supply of ignited gas will be collected in the cavity 36 and be transferred by valve movement to cylinder C to explode

another charge and so on during the opera- 30 tion of the engine.

What I claim is:—

1. In an explosive engine having an elongated explosion chamber, means for igniting the charge at one end of the elongation, and means for subsequently igniting the charge at the other end of the elongation. 35

2. In an explosive engine having an elongated explosion chamber, means for igniting the charge at one end of the elongation by 40 products of combustion of a previous explosion and at the other end by an electric spark.

3. In an explosive engine having an elongated explosion chamber, means for igniting the charge at one end of the elongation by the products of combustion of a previous explosion and thereby raising the compression in said chamber, and an electric sparker for subsequently igniting the charge at the 45 other end of the elongation. 50

In testimony whereof I affix my signature in the presence of two subscribing witnesses.

DORSEY FROST ASBURY.
